UNITED STATES PATENT OFFICE.

EMANUEL LINHARDT, OF NEW YORK, N. Y.

PASSENGER CONTROL.

No. 922,170.

Specification of Letters Patent.

Patented May 18, 1909.

Application filed March 17, 1909. Serial No. 483,902.

To all whom it may concern:

Be it known that I, EMANUEL LINHARDT, a citizen of the United States, and a resident of the city of New York, borough of Manhattan, in the county and State of New York, have invented a new and Improved Passenger Control, of which the following is a full, clear, and exact description.

The invention relates to railways, and its object is to provide a new and improved passenger control for conveniently and quickly handling passengers in the stations of underground and elevated railways, with a view to facilitate the loading and unloading of the cars without discomfort to the passengers entering or leaving the cars.

For the purpose mentioned the passengers leave the car through a door at one end, while the passengers enter the car through a door at the opposite end, so that the passengers entering the car are kept completely separate from the passengers leaving the car by the use of a passage formed of railings erected on the station platform.

A practical embodiment of the invention is represented in the accompanying drawing forming a part of this specification, in which the figure is a perspective view of the improvement as applied.

The edge of the station platform A is close to the cars B, B' of a train stopping at a station at predetermined points, each car having at its forward end an exit door C and at the rear end an entrance door D, so that the passengers leaving the car at the station pass through the door C while the passengers entering the car from the platform A pass through the door D.

In order to keep the passengers leaving the car and those that enter the car completely separate, use is made of a passageway formed of a main railing E and a second or outer railing F, the main railing E extending along the edge of the platform A from a point adjacent to the exit door C, terminating at one side of the entrance door D, as plainly indicated in the drawing. The outer railing F erected on the platform A is a short one and parallel with the rear end of the main railing E, to then terminate in a forwardly curved portion F', terminating at the edge of the platform A at the other side of the entrance door D. Now by the arrangement described the persons intending to enter the car B or B' from the station platform A pass between the railings E and

F and then through the door D into the rear end of the car, while the passengers leaving the car B pass through the front door C onto the platform A, and owing to the outer railing F these persons are kept separate completely from the persons entering the rear door D of the next car ahead.

In case main line and side line trains stop at the station, it is necessary to separate the persons for the two lines, and for this purpose use is made of an intermediate dividing railing G erected on the platform A between the railings E and F. Thus passengers intending to board a main line car pass between the railings E and G, while persons intending to board a car for the side lines pass between the railings F and G, and consequently when the corresponding car for either the main line or the side line stops at the station, the persons for the corresponding car can readily pass through the door D into the car.

The forward end of the main railing E is provided with a short angular railing H, extending inward on the platform A, so that the persons leaving the car through the door C are guided straight ahead, so as not to come in contact with the persons along the railings E, F, and G, and intending to enter the cars.

By the arrangement described, a simple and inexpensive but very efficient means is provided for controlling the persons leaving and entering cars at a station, without the slightest discomfort to such persons.

Having thus described my invention, I claim as new and desire to secure by Letters Patent:

1. A railway having a station platform and passages thereon, one passage for each car, and each passage having a longitudinal straight main railing along the edge of the platform and terminating at one end a distance from the exit door of a car of a train when at a standstill at the station, the other end of the main railing terminating adjacent to the one side of the entrance door of the car, and an outer railing parallel to the rear end of the said main railing and having a curved portion leading to the edge of the platform at the opposite side of the said entrance door.

2. A railway having a station platform and passages thereon, one passage for each car, and each passage having a longitudinal straight main railing along the edge of the

platform and terminating at one end a distance from the exit door of a car of a train when at a standstill at the station, the other end of the main railing terminating adjacent 5 to one side of the entrance door of the car, an outer railing parallel to the rear end of the said main railing and having a curved portion leading to the edge of the platform at the opposite side of the said entrance door, and an intermediate railing intermediate 10 the said main railing and the said outer railing, the forward end of the said intermediate railing being approximately opposite the beginning of the curved portion 15 of the said outer railing.

3. A railway having a station platform and passages thereon, one passage for each car, and each passage having a longitudinal straight main railing along the edge of the 20 platform and terminating at one end a distance from the exit door of a car of a train when at a standstill at the station, the other

end of the main railing terminating adjacent to one side of the entrance door of the car, an outer railing parallel to the rear end of the said main railing and having a curved portion leading to the edge of the platform at the opposite side of the said entrance door, and an angular railing extending at angles from the said main railing at the end adjacent to the exit door of the car, thus leaving a free passageway for the passengers leaving the exit door of the car, the said passageway extending between the said angular railing and the curved portion of the 30 next outer railing.

In testimony whereof I have signed my name to this specification in the presence of two subscribing witnesses.

EMANUEL LINHARDT.
